UNITED STATES PATENT OFFICE.

EUGENE F. OSBORNE, OF CHICAGO, ILLINOIS, ASSIGNOR TO THE OSBORNE STEAM ENGINEERING COMPANY, OF CHICAGO, ILLINOIS, A CORPORATION OF ILLINOIS.

METHOD OF SUPERHEATING STEAM.

SPECIFICATION forming part of Letters Patent No. 762,248, dated June 7, 1904.

Application filed October 20, 1899. Renewed April 8, 1901. Serial No. 54,920. (No model.)

To all whom it may concern:

Be it known that I, EUGENE F. OSBORNE, of Chicago, in the county of Cook and State of Illinois, have invented certain new and useful Improvements in Methods of Producing Superheated Steam; and I do hereby declare that the following is a full, clear, and exact description thereof, reference being had to the accompanying drawings, and to the letters of reference marked thereon, which form a part of this specification.

This invention relates to a novel method of producing superheated steam for use in steam-engines whereby a greater expansion of the steam may be secured and more power generated therefrom.

In carrying out the method constituting my invention I proceed generally as follows: Heat is first applied to a body of water to generate steam therefrom. A fluid heat-transmitting medium is employed, such as brine or oil or one having a boiling-point higher than water. Said heat-transmitting medium is contained within a circuit, through which it constantly passes or circulates. At one part of the circuit heat is applied to the medium and at another part thereof heat is transmitted from said medium to the steam to be superheated, said transfer of heat taking place outside of the space in which the steam is generated.

The process includes as an additional step the variation of the intensity of the heat applied to the medium to maintain constant the temperature of the superheated steam, the intensity of the heat applied being lessened when the temperature of the superheated steam rises above a predetermined point and being increased when such temperature falls below such point. By the method thus outlined,

therefore, I am enabled to maintain the superheated steam constantly at a desired temperature by controlling the intensity of the heat applied to the circulating medium to accord with the temperature of the steam after it has been superheated. To render automatic the control of the intensity of the heat applied to the heat-transmitting medium, I propose, further, to apply force derived from the varia-

tions in temperature of the superheated steam to so control the intensity of the heat applied to the heat-transmitting medium.

The invention consists in the matters hereinafter set forth, and more particularly pointed out in the appended claims.

I have shown in the drawing one form of apparatus which may conveniently be employed for carrying out my novel method, said drawing showing diagrammatically a steam-superheating device and illustrating the manner in which it may be connected with a steam-boiler, the latter being indicated in dotted lines.

As shown in said drawing, A designates a steam-generator, which is designed to supply steam to operate an engine in the usual manner.

B designates a cylindric or other shaped casing, which is closed at its ends by end walls b b' and which may be supported in any suitable manner. Said casing is provided internally thereof with two diaphragms B' B'', which divide the casing into an intermediate chamber B³ and two end chambers B⁴ and B⁵.

C designates a plurality of parallel tubes which extend between the diaphragms B' B'', and open through said diaphragms, so as to be in communication with the end chambers B⁴ and B⁵ and to afford communication between said chambers.

D designates a pipe leading from the boiler A and discharging to and communicating with the lower end of the intermediate chamber B³. Said pipe is herein shown as unvalved, but may be provided with a valve, if desired. E designates a pipe which leads from the upper end of said intermediate chamber B³ and is adapted for connection with the steam-chest of an engine. (Not shown.)

F designates a pipe which leads from the lower end of the lower chamber B⁴ and terminates at its lower end in a coil F', and F'' designates a pipe which leads from the opposite end of the coil and extends upwardly to and is in communication at its upper end with the upper end chamber B⁵ of the casing B. The coil F' is herein shown as located within a chamber or inclosure G. Said coil is adapted

to be subjected to the action of a heating medium and is shown as placed over a gas or vapor burner H, located in the bottom of the chamber G and supplied with fuel through the medium of a supply-pipe H', which may be connected at its end remote from the chamber G with a suitable source of fuel-supply.

I designates a thermostat, which is located within a fitting E', forming part of the steam-pipe E, leading from the upper end of the intermediate chamber B³ to the steam-chest of the engine. Said thermostat is operatively connected with the upper end of a rod J, the lower end of which rod is connected with a valve H², which is located within the fuel-supply pipe H' and by means of which the supply of fuel to the burner H is controlled.

H³ is a pipe leading from the supply-pipe H' at a point outside of the valve H² to a burner-jet h, located close to the annular burner H. Said pipe H³ is shown as supplied with a regulating-valve h'. The pipe H³ is intended to be kept open and to afford a constant supply of gas to the burner-jet h, which will always remain lighted and insures the relighting of the main burner in case the supply of gas thereto should be entirely cut off temporarily by the action of the thermostat.

The pipe F, coil F', pipe F², the end chambers B⁴ B⁵, and the tubes C constitute a heat-conducting circuit, while the pipe D, chamber B³, and pipe E constitute a passage for steam by means of which the same is brought into heat-transmitting relation to the heat-conducting medium circulated in the heat-conducting circuit. Said heat-transmitting medium receives heat from the burner H and is caused to circulate continuously through its circuit so long as the heat is applied thereto. The steam is continuously passed over the tubes C of the heat-transmitting-medium circuit and a portion of the heat of said medium is given off to the steam, with the result of raising the temperature of the steam or superheating the same. The liquid used as a heat-conducting medium is one which has a boiling temperature considerably higher than the water from which the steam is generated, so that a higher temperature may be maintained in the superheater-circuit than in the steam generator or boiler, with little pressure in said circuit. The liquid employed as a heat-conducting medium may be linseed-oil, brine, a metal having a low fusing-point and a high boiling-point, or any other suitable fluid.

K designates a safety-valve, which is in communication with the upper chamber B⁵ of the casing and which provides against injury to the casing from pressure of vapor or gas arising from the heat-conducting medium.

As before stated, the thermostat I is located within the discharge-pipe E of the superheating-chamber or that leading to the point of use or consumption of the superheated steam, so as to be subjected to the full influence of

the superheated steam after it leaves said heating-chamber. Said thermostat when installed in the apparatus will be adjusted in a manner to be actuated at a selected temperature or at a temperature at which it is desired to maintain the steam in the pipe E, so that it will be operated to actuate the valve upon a variation from such selected or given temperature either above or below such temperature. In other words, when the temperature of the steam exceeds that which has been predetermined the thermostat operates to close the valve, so as to decrease or cut off the supply of fuel to the coil F', while when said temperature is reduced below that of such predetermined point the thermostat operates to open the valve and permit an increased supply of fuel to said burner with a corresponding increase in the heat given to the circulating medium by which the superheating-chamber is heated.

While I have herein shown the heat-conducting circuit as supplied by heat from a vapor or gas burner, it will be obvious that the source of heat to the circulating medium may be the furnace which supplies the boiler A with heat. In this case a flue may be directed from said furnace to a casing, such as the casing G, and said flue provided with a damper, which may be connected with the thermostat and operated in a manner similar to that in which the valve H² is operated. Moreover, in case the regulation of the heat applied to the transmitting medium is not required such heat may be derived from the furnace itself without the intervention of dampers and regulating apparatus.

One of the important advantages arising from the use of the method above set forth is that the source of heat is entirely outside of and independently controllable with respect to the heat applied to the steam-generator, so that the conditions which govern the heating of the steam-generator will have no effect on the heat which is applied to the circulating medium of the conducting-circuit. Moreover, said heat-conducting circuit being subjected only to a moderate degree of heat is more durable than where the said circuit is subjected to the heat applied to the main generator.

An important advantage of using a heat-transmitting medium having a higher boiling-point than that of water is that the required heat may be imparted therethrough to the steam without materially vaporizing the medium, and therefore without producing any considerable pressure in the superheating-medium circuit. The walls of said circuit may therefore be safely made relatively thin, and thereby facilitate the transmission of heat therethrough to the steam which passes therover.

Obviously in the employment of the apparatus described for carrying out my novel

method the thermostatic controlling device employed to govern the supply of fuel to the burner serves as a means of utilizing the force derived from variations in the temperature of the superheated steam to accomplish this end. My novel method, therefore, not only includes the step of varying the intensity of the heat applied to the heat-transmitting medium, but also, as an additional feature, the step by

10 which such control is rendered automatic—namely, the application of force derived from variations in the temperature of the superheated steam to so control the intensity of such heat.

15 It is to be understood, however, that force derived from variations in the temperature of the superheated steam may be utilized for so controlling the intensity of the heat otherwise than through the use of such thermostatic.

20 It will of course be understood that the superheating device will be properly insulated from the surrounding atmosphere. Such insulation may consist of an asbestos investment or like material.

25 I claim as my invention—

1. The method of superheating steam, which consists in applying heat to a heat-transmitting medium, transmitting heat from said medium to the steam to be superheated, and 30 varying the intensity of the heat applied to said medium upon a decrease or increase of the temperature of the superheated steam to maintain constant the temperature of such superheated steam.

35 2. The method of superheating steam which

consists in circulating in a closed circuit a fluid heat-transmitting medium, applying heat to said medium at one part of said circuit, transmitting heat from said medium to the steam to be superheated at another part of the 40 said circuit, and varying the intensity of the heat applied to the said medium to maintain constant the temperature of the superheated steam.

3. The method of superheating steam which 45 consists in applying heat to a fluid heat-transmitting medium, transmitting heat from said medium to the steam to be superheated, and applying force derived from variation in the temperature of the superheated steam to vary 50 the intensity of the heat applied to said medium and to thereby maintain constant temperature of said superheated steam.

4. The process of producing superheated steam which consists in applying heat to an 55 agent to produce steam and thereafter subjecting the steam in a space separate from the space in which it is generated to heat from a superheating agent, the correlative steam pressure of which agent is less than that of 60 the agent from which the steam is produced.

In testimony that I claim the foregoing as my invention I affix my signature, in presence of two witnesses, this 13th day of October, A. D. 1899.

EUGENE F. OSBORNE.
